VARIABLE OSCILLATING GEAR

Joseph D. Kreis, Cleveland, Ohio

Application October 9, 1946, Serial No. 702,154

17 Claims. (Cl. 74—793)

1

This invention relates to variable oscillating gear mechanisms, that is, devices for converting continuous rotary motion into oscillating rotary motion, having a provision for varying the amplitude of the oscillating motion. In its preferred embodiment, as described herein, the invention is applied to a drive for the agitator of a washing machine, but, as will be seen, the mechanism may be employed in various environments.

An object of the invention is to provide a mechanism for converting continuous rotary motion into oscillating rotary motion.

Another object of the invention is to provide such a mechanism in which the amplitude of the oscillating movement may be varied while the mechanism is in operation.

Another object of the invention is to provide means for rotational coupling between two bodies having offset axes of rotation.

Another object of the invention is to provide a mechanism for converting continuous rotary motion into oscillating rotary motion which will be compact, reliable and durable, and will be economical of manufacture.

Another object is to provide a mechanism which is adapted for enclosure in a driven rotatable housing which may be sealed and contain a bath of lubricant.

A further object of the invention is to provide an improved driving mechanism for a washing machine agitator.

Other objects and advantages more or less ancillary to the foregoing and the manner in which all the various objects are realized will appear in the following description, which, considered in connection with the accompanying drawings, sets forth the preferred embodiment of the invention.

Referring to the drawings:

Fig. 1 is an elevational view, partly in section, illustrating the application of the invention to a washing machine;

Fig. 2 is a sectional view of a fragmentary portion taken on a plane indicated on a line 2—2 of Fig. 1;

Fig. 3 is a plan view of a portion of the mechanism showing the eccentric planet gear;

Fig. 4 is a view of the concentric planet gear as seen from below;

Fig. 5 is a vertical section through the planet gears taken on a plane indicated by the lines 5—5 in Fig. 3; and

Fig. 6 is a vertical section through the planet gears taken on a plane indicated by the line 6—6 in Fig. 3.

2

Referring to Fig. 1, the invention is illustrated as incorporated in a conventional washing machine having a tub 11 mounted on a frame 12 and including a drive pulley 13 associated with a motor (not shown) and a power take-off pulley 14 for the operation of a wringer (not shown). The gearing which forms the subject of this invention is principally enclosed in a housing 15 in the form of a hollow pulley. The agitator shaft 16 extends upward from the housing through a gland in the bottom of the tub. The housing 15 comprises two flanged sheet metal stampings 16 and 17 (Figs. 1 and 6) which are annular in form and struck with the marginal portions thereof directed inwardly to form the sides 18 of a V-belt pulley when the two stampings are assembled in opposed relation to each other. The two stampings 16 and 17 are retained in clamped relation by conical-headed screws 19 seated in openings 20 in the stampings and threaded into spacing sleeves 22. A gasket 23, preferably composed of synthetic rubber, is clamped between the opposed edges of the flanges 18, providing a seal against leakage of oil from the housing. The lower hub 25 of the housing 15 is formed by a frusto-conical malleable casting having a peripheral groove 21 therein for the reception of the inner circumference of the stamping. The walls of the casting 25 defining the groove 21 are rolled or pressed into intimate oil tight engagement with the stamping 17 to effect the support thereof. The upper hub 28 is sealed into the upper stamping 16 in the same manner. The hub 28 is provided with a counterbored central opening 29 into which is pressed a flanged bushing 30 which forms a radial and thrust bearing surface for rotational support of the housing 15. The bushing 30 is journaled on a flanged sleeve 31 threaded onto a depending cylindrical portion 32 of a spider 33. The spider is formed with a cylindrical flange 34 circumjacent the hub 28 which defines a pocket between the flange and hub for the retention of packing 36. The spider 33 is further formed with a plurality of equally spaced ears 37 having cups 38 in the extremities thereof for the reception of vibration-dampening rubber bushings 39 which are compressively supported in the cups 38 and in similar cups 40 in a bearing member 41. The bearing 41 constitutes the support for the agitator shaft 42. Cap screws 43 retain the bearing member 41 and the spider 33 on the frame member 12, the cap screws being passed through openings 44 in the cups 40 and being received in threaded openings 46 in the cups 38. The bushings 39 are molded with peripheral grooves therein for the retention of the

marginal edges of openings 47 in the frame member 12. The agitator shaft 42 is sealed against leakage by packing 48 retained by a sleeve 49 threaded into a cup 50 formed in the central portion of the bearing member 41. The bottom 51 of the tub is retained between a flange 51a of the casting and a nut 52 threaded onto the sleeve 49. The agitator shaft passes through an opening 53 in the bottom of the cup 50, through the casting 33 and into the housing 15.

The agitator shaft is driven by a sun pinion 56 (Fig. 6) formed integral with a sleeve 57 splined to the lower end of the shaft (Fig. 1) and retained by a spring collar 58. The lower end of the shaft 42 is journaled in a flanged bushing 59 pressed into a bore in a central cylindrical portion 61 of the hub casting 26. A thrust washer 62, keyed to the sun pinion, by a tab which is bent for engagement between teeth in the face of the pinion, is interposed between the pinion and the thrust bearing face of the bushing 59.

Oil may be drained from the housing through a passage 64 in the hub 26 by removing a plug 66 at the bottom of the hub. A plug 67 threaded into the upper stamping 16 of the housing is provided to facilitate replenishment of the oil. The mechanism preferably runs in a bath of oil.

The oscillating gear contained in the housing 15 is based upon the principles disclosed in my copending application Serial No. 667,965, filed May 7, 1946, for Oscillating gear. In accordance with the principles therein set forth, the present apparatus includes a fixed sun pinion 93 mounted in the spider 33 and in coaxial relation with the agitator shaft 42 and the agitator sun pinion 56. A planet gear 87 is concentrically mounted with respect to and engages the fixed sun pinion 93, the housing 15 serving as a carrier. A second planet gear 68 engages the agitator sun pinion 56 and is mounted for eccentric rotation with respect to a support boss 73, while the axis of the gear is constrained to move along a path concentric with the agitator pinion 56 by a yoke 81. The planet gears 68 and 87 are rotatively coupled by a rack and pinion arrangement which enforces equal rotation of the two gears while accommodating relative displacements of their axes. Rotation of the carrier is then translated into oscillatory displacement of the agitator shaft 42 by reason of the eccentricity of the axis of the planet gear 68 with respect to its center of rotational support, i. e. the boss 73.

The planet gear 68 (Figs. 3, 5, and 6) which meshes with the pinion 56 on the agitator shaft, is supported by a hub 69 which is slidably radially of the gear, the hub being rotatably supported on an arm 71 pivoted in the housing. The arm 71 is formed with a boss 72 at one end thereof which is bored for pivotal movement around one of the sleeves 22 in the housing. The opposite end of the arm is formed with a cylindrical boss 73 which provides a radial support for the hub 69 within which it is mounted. The hub has a lower flange 74 thereon which is borne by the surface of the arm circumjacent the boss 73, and has an upper flange 76 thereon which supports the gear 68.

The central portion 68a (Figs. 3 and 5) of the web of gear 68 is elevated, and is formed with a slot 77 therein directed radially of the gear. The upper portion of the hub 69 is formed with a diametral wall 78 having a rack 79 machined in the upper surface thereof, the rack being disposed in a plane slightly above the flange 76, and being slidably received in the slot 77. Engagement of the rack 79 within the slot constrains the hub

69 from rotation relative to the gear 68. The rack teeth form a part of the mechanism for shifting the hub 69 radially of the gear 68 to vary the eccentricity of the hub with respect to the axis of the gear and the consequent amplitude of the oscillatory motion. The flange 76 is cut away at one end of the rack bar 78 to permit maximum movement of the hub 69 to the right as will be seen in Fig. 6.

10 The gear 68 is maintained in mesh with the pinion 56 by a yoke 81 having a collar 82 at its inner end pivoted on a sleeve 83 on the agitator shaft 42, and formed with a bore 84 in its outer end which provides a bearing for the machined 15 concentric surface 86 at the periphery of the elevated central portion 68a of the planet gear 68.

Under the combined action of the arms 71 and 81, the planet gear 68 is constrained with respect to the housing 15 and the agitator shaft 42 since 20 its center moves in an arc about the shaft, whereas its eccentric hub swings in an arc about a sleeve 22 of the housing, that is, substantially radially of the housing.

The planet gear 87 (Figs. 4, 5, and 6) embodies 25 a bored and faced hub 88 journaled on a flanged bearing sleeve 89 fixed in the housing. The sleeve 89 is formed with a conical bore 90 constituting the seat for a conical flange 91 struck from the marginal edge of an opening in the upper face 16 of the housing. The parts are 30 retained in assembled relation by a plug 92 engaged with the flange 91 and threaded into the sleeve. The planet gear 87 meshes with the fixed pinion 93 (Figs. 1 and 6) which is retained 35 in the portion 32 of the spider 33, preferably by being bonded therein during the die-casting of the member 33.

A stroke-adjusting pinion 94, mounted on the shaft 42, and rotatable independently of the 40 shaft, is formed integral with the sleeve 83 and with a sleeve 96 which extends upwardly into the spider 33 through the fixed pinion 93.

The adjusting pinion 94 remains stationary 45 except when the amplitude of the oscillation is adjusted. The pinion 94 has the same number of teeth as the pinion 93.

A ring gear 97, having the same diameter and 50 number of teeth as the planet gear 87, is mounted on the lower face of the gear 87 in mesh with the adjusting pinion 94.

The bore of the ring gear is rotatably received 55 on a turned outer face 98 of the web of the planet gear, and is retained thereon by buttons 99 threaded into the planet gear, the heads of which overlie the inner edge of the ring gear.

The means for coupling the two planet gears 60 for concurrent rotation must accommodate lateral displacement of the two gears resulting from the eccentricity of the axes of the planet gears. The coupling comprises two parallel racks 101 and 102 formed on the upper face of the gear 68, and two parallel racks 103 and 104 on the lower face of the gear 87 within the ring gear 97. The racks 101 and 102 are parallel to, and equally spaced from, the sliding rack 79 on the hub 69.

65 When the gearing is assembled the racks 101 and 103 and the racks 102 and 104 are parallel and disposed in face-to-face relation. The intermediate coupling member comprises a floating shaft 106 having wide-faced pinions 107 and 108 70 splined on each end of the shaft. The pinion 107 meshes with the racks 101 and 103, and the pinion 108 meshes with the racks 102 and 104. Rollers 109 mounted for rotation on the shaft 106 and engaged with the faces of the planet 75 gears are provided to maintain the pinions in

proper lineal relation and prevent the teeth from bottoming in the racks.

Relative motion between the two planet gears may be considered with respect to a component parallel to the racks and a component in quadrature to the racks. The parallel component is accommodated by rotation of the pinions and shaft, the quadrature component by sliding movement of the pinions and shaft along the shaft axis. In this connection, the rollers 109, by engagement with the sides of the racks, prevent the intermediate member from sliding out of engagement with the racks. No relative rotation of the planet gears is possible, since the pinions 107 and 108 are mounted for simultaneous rotation with the shaft 106.

The means for varying the eccentricity of the hub 69 with respect to the axes of the gear 68 includes, as has been stated, the rack 79 on the hub 76. The rack is shifted by a pinion 111 rotatably mounted on the shaft 106 between the rollers 109. This pinion also meshes with a rack 112 cut in a bar 113 slidably mounted in a diametral path in the lower face of the gear 87. The ends of the bar 113 are formed for abutment against the spiral cam surfaces 114 and 115 formed in the inner edge of the ring gear 87. Thus, by rotating the ring gear with respect to the planet gear, the rack 112 is shifted radially of the gear, rotating the pinion 111 and shifting the rack 79 and hub 69 radially of the lower planet gear.

Normally, the gears 87 and 97 do not rotate relative to each other, and the amplitude of oscillation of the shaft 42 remains constant. To adjust the amplitude, the pinion 94 is turned, which incidentally may be accomplished during the operation of the machine. The pinion 94 is integral with the sleeve 96, the upper end thereof being machined to form a worm wheel 116 thereon (Figs. 1 and 2) disposed within the spider 33. A worm 117, cut into a shaft 118, meshes with and rotates the worm wheel 116. The shaft 118 is enclosed in a cylindrical housing 119 formed integral with the spider 33. A pin 121 in the housing, engaged in a groove 122 in the shaft, retains the shaft against axial displacement.

The outer end of the shaft 118 is coupled, by a shaft 123 (Fig. 1) and universal joints 124 and 125, to the spindle 126 of an adjusting knob 127. The spindle 126 is journaled in a boss 128 formed in the flange of the frame member 12, and is retained by a star washer 129 secured by a nut 131. A detent 132 having the inner end thereof seated upon the boss 128, and its intermediate portion bent to project through an opening 133 in the frame is engaged with the star washer 129. The detent is held within the opening 133 by a compression spring 134 engaged between the hub of the detent and the knob 127. The periphery of the knob is machined with a groove therein which is disposed in telescopic engagement with a cylindrical portion 136 of the frame. By pressing the knob inward, the star washer 129 may be released from the detent, and the shaft 123 rotated. The joints 124 and 125 are designed for sufficient telescopic movement to facilitate such action.

Alternately, by exerting an outward force against the protruding end 137 of the detent, the star washer may be released. Such operation may be effected by any well known form of linkage which if desired may be associated with a time-controlled actuating mechanism. In this event, the reaction of the work done by the agi-

tator shaft will cause the hub 69 to return to the center of the gear 68, terminating the oscillating movement. For this action to take place, the gears 116 and 117 must be so designed as to be reversible.

If desired, the gears 116 and 117 may be made irreversible and the detent mechanism be omitted.

Preferably, the ratio of gear 87 to pinion 93 is slightly different from the ratio of gear 68 to pinion 56, with the result that the agitator shaft will "creep" slightly. The amount of creeping movement may be determined by well-known formulas for the action of compound planetary gears, as set out in the abovementioned copending application.

One or more of sleeves 22 (Fig. 1) opposite the planet gears may be enlarged to balance the weight of the planet gears, or two sets of planet gears in opposite sides of the housing may be provided to secure a balanced mechanism.

Operation

While it is believed the operation of the mechanism disclosed herein will be clear to those skilled in the art from the foregoing description, a concise consecutive description of the operation follows.

Assuming that the knob 127 is set for no oscillation of the agitator shaft 42, the hub 69 will be concentric with the gear 68. If now the motor is energized to rotate the housing 15, the planet gears 87 and 68 are revolved around the sun gears 93 and 56 respectively by the housing 15. The two planet gears are constrained to rotate equally about their axes (that is, with respect to the housing 15) by the intermediate coupling member comprised by shaft 106 and pinions 107 and 108 meshing with the racks on the faces of the planet gears. The sun gear 93 is fixed, and therefore, by the usual operation of a compound planetary or epicyclic gearing, the center gear 56 either remains stationary or rotates at a constant rate. If the ratio of sun gear 93 to planet gear 87 equals the ratio of sun gear 56 to planet gear 58, the sun gear 56 will remain stationary. By constructing the gearing so that these two pairs of gears are of slightly different ratio, as stated above, the sun gear 56 and the agitator shaft 42 on which it is mounted will be caused to rotate slowly at a constant rate or "creep."

The ring gear 97 is in mesh with the pinion 94 which remains fixed. Since the pinions 93 and 94 are of the same number of teeth and the planet gear 87 and ring gear 97 are of the same number of teeth, the gears 87 and 97 rotate together and remain in the same relative position.

In order to cause oscillation of the agitator shaft 42, the hand wheel 127 is rotated, rotating the pinion 94 through the following chain of mechanism: shafts 126, 123, and 118, gears 117 and 116, and sleeve 96, with which the pinion 94 is integral. This rotation of the pinion 94 relative to the fixed pinion 93 causes rotation of the ring gear 97 with respect to the planet gear 87; and, by this rotation, the bar 113 on which the rack 112 is formed is reciprocated across the face of the gear 87 by the internal cam surfaces 114 and 115 of the ring gear. We may assume that the movement is sufficient to shift the rack 112 to the position illustrated in Fig. 6. As the rack is moving inwardly, it is in mesh with the pinion 111 which thus rotates about the shaft 106. The pinion 111 meshes with the rack 79 on the hub 69, shifting the hub away from the center of the planet gear 68 to an eccentric position such as illustrated in Fig. 6. This motion of the hub 69

with respect to the gear 68 is accommodated by rotation of the arm 71 on which the hub 69 is rotatably mounted about its pivot 22 (Fig. 3), and by circumferential movement of the gear 68 with respect to the housing 15. The link 71 maintains the hub at a fixed distance from its pivot 22 and the yoke 81 maintains the planet gear 68 at its set distance from the central axis of the shaft 42. Depending upon the actual angular relation of the planet gears with respect to the housing 15, this shifting movement of the hub will cause more or less rotation of the planet gear 68 with respect to the housing and thus of the sun gear 56. This temporary rotation of the sun gear 56 is, of course, communicated to the agitator shaft 42 on which it is mounted. This displacement just mentioned ceases upon the termination of change in the position of the hub 69 with respect to the gear 68; but when the hub has been displaced to an off-set position, a continuous oscillating movement of the agitator shaft 42 is produced.

The underlying reason or principle of this action may be more easily understood by reference to the relatively simple mechanism of my above-mentioned copending application than by reference to the more complex mechanism disclosed here; and it is believed that it will be apparent to anyone who understands the said application.

However, in terms of the structure here presented, the action is as follows: Rotation of the housing 15 rolls the planet gear 87 and ring gear 97 as a unit around the fixed pinions 93 and 94, these planet gears rotating on the hub 89 fixed in the housing. The planet gear 68 is caused to rotate about the eccentric axis defined by the hub 69 at exactly the same rate as the planet gear 87 by the coupling between these two gears comprising the shaft 106 and the pinions 107 and 108 fixed thereon. This coupling accommodates relative displacement of the axes of the gears, however, both by rotation of the pinions 107 and 108 on the racks 101, 102, 103, and 104, and by sliding movement of the pinions longitudinally of and with the shaft 106, which is permitted by the fact that the pinions are of greater width than the racks. The planet gear 68, therefore, rotates uniformly with the planet gear 87 whatever the relative positions of the axes of those gears. However, since the axis of rotation of the planet gear 68 defined by the hub 69 is eccentric with respect to the axis of the gear 68 and since the axis of the gear 68 is constrained to move in a circle concentric with the agitator shaft 42, the uniform rotation of the planet gear 68 must cause a displacement of the hub 69 about the axis of the gear. By reason of the double constraint between the agitator pinion 56 and the planet gear 68 imposed by their teeth and the yoke 81, this displacement of the hub 69 is imparted to the agitator pinion as a variable motion, oscillatory in character. The average rate of rotation of the pinion 56 is either zero or a small rate, as previously set out in the description of operation of the gearing with the planet gear 68 centered.

The amplitude and frequency of the oscillatory movements and the rate of the creeping movement may be determined by the application of known principles of mechanism which have been set out for convenience in my above-mentioned copending application and need not be repeated here.

It will be apparent to those skilled in the art that for certain applications where no variation of the amplitude of oscillation is desired, many

of the principles of construction disclosed herein may be employed by omitting the parts of the device which adjust the amplitude. In such case, the type of coupling shown herein between the planetary gears may be retained, with omission of the pinion 101. With the pinion omitted, a single wide-faced rack on each planetary gear and a single coupling pinion, with rollers at the end of the pinion to retain it in engagement with the racks, may be used.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

I claim:

1. A variable oscillating gear mechanism comprising two sun gears, a planet gear meshing with each sun gear, a carrier on which the planet gears are mounted for revolution about the sun gears, means defining an axis of rotation for one planet gear adjustable radially of the said one gear, and means coupling the planet gears for concurrent rotation.

2. A variable oscillating gear mechanism comprising two sun gears, one of the sun gears being fixed, a planet gear meshing with each sun gear, a carrier on which the planet gears are mounted for revolution about the sun gears, means defining an axis of rotation for one planet gear adjustable radially of the said one gear, and means coupling the planet gears for concurrent rotation.

3. A variable oscillating gear mechanism comprising two coaxial shafts, a sun gear fixed on each shaft, a carrier rotatable about the axis of the shafts, a planet gear meshing with each sun gear, means constrained to rotation about the shaft axis with the carrier defining an axis of rotation for each planet gear, means coupling the planet gears for equal rotation about their respective axes, and means for adjusting the axis of rotation of one planet gear radially of the said one gear, whereby the said one gear may be given varying amounts of eccentricity with respect to that axis.

4. A variable oscillating gear mechanism comprising two coaxial shafts, one of the shafts being fixed, a sun gear fixed on each shaft, a carrier rotatable about the axis of the shafts, a planet gear meshing with each sun gear, means constrained to rotation about the shaft axis with the carrier defining an axis of rotation for each planet gear, means coupling the planet gears for equal rotation about their respective axes, and means for adjusting the axis of rotation of one planet gear radially of the said one gear, whereby the said one gear may be given varying amounts of eccentricity with respect to that axis.

5. A variable oscillating gear mechanism comprising two sun gears, a first planet gear meshing with one of said sun gears, a second planet gear meshing with the remaining sun gear, said second planet gear having an eccentric axis of rotation, a carrier in which the said planet gears are mounted for revolution about the sun gears, means coupling the planet gears for concurrent rotation about their axes, and means for varying the axis of eccentricity of the said second planet gear comprising a member movable radially of the gear, a member movable radially of the said first

planet gear, and means coupling the two members.

6. A variable oscillating gear mechanism comprising two sun gears, a first planet gear meshing with one of said sun gears, a second planet gear meshing with the remaining sun gear, said second planet gear having an eccentric axis of rotation, a carrier in which the said planet gears are mounted for revolution about the sun gears, means coupling the planet gears for concurrent rotation about their axes, and means for varying the axis of eccentricity of the said second planet gear comprising a first member movable radially of the gear, a second member movable radially of the said first planet gear, means coupling the two members, and a part rotatable about the axis of the said first planet gear for moving the second member.

7. A variable oscillating gear mechanism comprising two sun gears, a first planet gear meshing with one of said sun gears, a second planet gear meshing with the remaining sun gear, said second planet gear having an eccentric axis of rotation, a carrier in which the said planet gears are mounted for revolution about the sun gears, means coupling the planet gears for concurrent rotation about their axes, and means for varying the axis of eccentricity of the said second planet gear comprising a first member movable radially of the gear, a second member movable radially of the said first planet gear, means coupling the two members, a gear rotatable about the axis of the said first planet gear for moving the second member, and a pinion rotatable about the axis of the sun gears for rotating the last-named gear with respect to the planet gear.

8. An oscillating gear mechanism comprising a fixed shaft, a rotatable shaft coaxial with the fixed shaft, a housing rotatable on the shafts, a sun gear fixed on each shaft within the housing, a first planet gear meshing with one sun gear and rotatable about a shaft fixed in the housing, a second planet gear meshing with the other sun gear, a shaft for the second planet gear mounted for movement radially of the housing and constrained to rotate therewith, and means coupling the planet gears for concurrent rotation comprising a rack on each planet gear, each rack being parallel to and opposing the rack on the other gear, and a pinion meshing with the racks of both planet gears, the pinion being of greater width than the racks.

9. A variable oscillating gear mechanism comprising two coaxial shafts, a carrier rotatable on the shafts, a sun gear fixed on each shaft, a first planet gear meshing with one sun gear and rotatable about a shaft fixed in the carrier, a second planet gear meshing with the other sun gear, a hub for the said second planet gear mounted in the gear for radial movement thereof, said hub being constrained with respect to said carrier, a yoke for the second planet gear rotatable about the axis of said coaxial shafts and defining an axis of rotation for said second planet gear through the axis of that gear, means coupling the planet gears for concurrent rotation comprising a rack on each planet gear, each rack being parallel to and opposing the rack on the other gear, and a pinion meshing with the racks of both planet gears, the pinion being of greater width than the racks; and means for varying the eccentricity of the hub of the second planet gear with respect to the axis of that gear.

10. A variable oscillating gear mechanism comprising two coaxial shafts, a carrier rotatable on

the shafts, a sun gear fixed on each shaft, a first planet gear meshing with the fixed sun gear and rotatable about a shaft fixed in the carrier, a second planet gear meshing with the other sun gear, a hub for the said second planet gear mounted in the gear for radial movement thereof, said hub being constrained with respect to said carrier, a yoke for the second planet gear rotatable about the axis of said coaxial shafts and defining an axis of rotation for said second planet gear through the axis of that gear, means coupling the planet gears for concurrent rotation comprising a rack on each planet gear, each rack being parallel to and opposing the rack on the other gear, and a pinion meshing with the racks of both planet gears, the pinion being of greater width than the racks; and means for varying the eccentricity of the hub of the second planet gear with respect to the axis of that gear comprising a member slidable radially of the first planet gear, a member slidable radially of the second planet gear and means coupling the two members.

11. An oscillating gear mechanism comprising two coaxial shafts, a housing rotatable on the shafts, a sun gear fixed on each shaft within the housing, a first planet gear meshing with one sun gear and rotatable about a shaft fixed in the housing, a second planet gear meshing with the other sun gear, a shaft for the said second planet gear mounted for movement radially of the housing and constrained to rotate therewith; and means coupling the planet gears for concurrent rotation comprising a pair of parallel racks on each planet gear, each rack being parallel to and in opposition to a rack on the other gear, a floating shaft perpendicular to the racks, and a pinion fixed on each end of the shaft meshing with a rack of each planet gear, the pinions being of greater width than the racks.

12. An oscillating gear mechanism comprising a fixed shaft, a rotatable shaft coaxial with the fixed shaft, a housing rotatable on the shafts, a sun gear fixed on each shaft within the housing, a first planet gear meshing with the fixed sun gear and rotatable about a shaft fixed in the housing, a second planet gear meshing with the rotatable sun gear, a shaft for the said second planet gear mounted for movement radially of the housing and constrained to rotate therewith; and means coupling the planet gears for concurrent rotation comprising a pair of parallel racks on each planet gear, each rack being parallel to and in opposition to a rack on the other gear, a floating shaft perpendicular to the racks, and a pinion fixed on each end of the shaft meshing with a rack of each planet gear, the pinions being of greater width than the racks.

13. A variable oscillating gear mechanism comprising two coaxial shafts, a housing rotatable on the shafts, a sun gear fixed on each shaft, a first planet gear meshing with one sun gear and rotatable about a shaft fixed in the housing, a second planet gear meshing with the other sun gear, a hub for the said second planet gear mounted for movement radially of the housing and constrained to rotate therewith, a yoke for the said second planet gear for the rotational constraint thereof with respect to said coaxial shafts, means coupling the planet gears for concurrent rotation, and means for varying the eccentricity of the hub of the second planet gear with respect to the axis of that gear.

14. A variable oscillating gear mechanism comprising a fixed shaft, a rotatable shaft coaxial

with the fixed shaft, a housing rotatable on the shafts, a sun gear fixed on each shaft within the housing, a first planet gear meshing with the fixed sun gear and rotatable about a shaft fixed in the housing, a second planet gear meshing with the rotatable sun gear, a yoke rotatably mounted about the said coaxial shafts and rotatably supporting said second planet gear, a hub for the second planet gear mounted in the gear for movement radially thereof and mounted for movement radially of the housing and constrained to rotate therewith, means coupling the planet gears for concurrent rotation, and means for varying the eccentricity of the hub of the second planet gear with respect to the axis of that gear.

15. A variable oscillating gear mechanism comprising a fixed shaft, a rotatable shaft coaxial with the fixed shaft, a housing rotatable on the shafts, a sun gear fixed on each shaft within the housing, a first planet gear meshing with the fixed sun gear and rotatable about a shaft fixed in the housing, a second planet gear meshing with the rotatable sun gear, a yoke rotatably mounted about the said coaxial shafts and rotatably supporting said second planet gear, a hub for the second planet gear mounted in the gear for movement radially thereof and mounted for movement radially of the housing and constrained to rotate therewith; means coupling the planet gears for concurrent rotation comprising a pair of parallel racks on each planet gear, each rack being parallel to and opposing a rack on the other gear, a floating shaft perpendicular to the racks, a pinion fixed on each end of the shaft meshing with a rack of each planet gear, the pinions being of greater width than the racks; means for varying the eccentricity of the hub of the second planet gear comprising a rack slidable radially of the first planet gear intermediate the aforementioned racks, a cam and cam follower for shifting the rack, a gear for operating the cam journalled in the housing, a pinion coaxial with the sun gears meshed with the cam operating gear, an actuator for the pinion, a rack

on the hub parallel to and opposing the rack slidable on the first planet gear, and a pinion free on the floating shaft intermediate the pinions fixed thereon and meshing with the slidable rack and hub rack.

16. A variable oscillating gear mechanism comprising a fixed shaft, a rotatable shaft coaxial with the fixed shaft, a housing rotatable on the shafts, the housing being conformed as a pulley, a sun gear fixed on each shaft within the housing, a planet gear meshing with each sun gear mounted within the housing and revolvable about the sun gears therewith, means providing one of the planet gears with an axis adjustable radially of the gear, and means coupling the planet gears for concurrent rotation.

17. A variable oscillating gear mechanism comprising a fixed shaft, a rotatable shaft coaxial with the fixed shaft, a housing rotatable on the shafts, the housing being conformed as a pulley, a sun gear fixed on each shaft within the housing, a planet gear meshing with each sun gear mounted within the housing and revolvable about the sun gears therewith, means providing one of the planet gear with an axis adjustable radially of the gear, and means coupling the planet gears for concurrent rotation, the housing being adapted to retain an oil bath.

JOSEPH D. KREIS.
